This invention relates to furnaces and provides an improved anchorage assembly for retaining a monolithic or brick-built refractory lining or wall inside a furnace casting or equivalent furnace structure.

In known furnace construction, a monolithic refractory lining is made in situ by casting, moulding or ramming refractory material over thermal insulation on the inside surface of a furnace casing so as to form a heat-resistant covering on the inside surface of the furnace.

A brick-built lining is made from preformed bricks which are built into a wall which lines thermal insulation on the furnace casing.

With either type of construction, monolithic or brick-built, it is necessary to provide a secure anchorage between the refractory lining and the furnace casing. Various types of metal anchors have been used for this purpose, usually involving embedding metal parts in a monolithic lining or using metal clamps or other anchor members embracing parts of so-called anchor tiles embedded in a monolithic lining or incorporated in a brick-built lining.

Existing anchorages are not entirely satisfactory, not allowing for relative movement which takes place during heating and cooling of furnace parts, such as between the refractory lining and furnace casing, with the result that strains may occur with consequent fracture of anchor tiles or other parts of the refractory lining.

The present invention provides an anchorage which will securely retain a furnace lining in place whilst allowing for relative movement due to thermal dimensional change.

According to the invention, an anchorage assembly, for a refractory lining of a furnace, comprises a refractory anchor body, with sides shaped to key with the refractory lining and having near one end thereof a transverse hole, and a metal link formed of at least two parts and providing a pair of substantially parallel limbs of which one limb can pass through the hole in the refractory anchor body with freedom for relative movement therein and the other limb can pass similarly through a corresponding hole in a bracket on the inside of the furnace casing or other structural furnace member.

Being made in at least two parts, the parallel limbs of the metal link can be inserted through the refractory anchor body and bracket holes when the anchor body is put in place during construction of the furnace lining. Once in place, the link retains the anchor body securely connected to the furnace casing but, the link limbs being movable in their respective holes, the anchor body has freedom for small relative movement due to differential thermal dimensional change when the furnace is first heated and thereafter in use of the furnace.

The invention will be further described with reference, by way of example, to the accompanying drawings, in which:

FIG. 1 is an isometric view of an anchorage assembly in a furnace wall shown in fragmentary cross-section,

FIG. 2 is a side elevation of part of the assembly of FIG. 1,

FIG. 3 is a sectional plan on the line III—III of FIG. 2,

FIG. 4 is a sectional plan, similar to FIG. 3, showing an alternative link construction and

FIG. 5 is another similar plan showing a further alternative link construction.

The part of a furnace wall shown by FIG. 1 consists of a sheet metal casing 1, a layer 2 of thermal insulating material and a monolithic lining 3 of refractory material anchored to the casing 1 by a so-called anchor tile 4. This kind of furnace wall is well known and the present invention is concerned only with the anchorage of the lining to the furnace casing or other part of the furnace structure, for example beams or joists of furnace ceilings or bearers of furnace arches.

The anchor tile 4 shown in FIG. 1 has its sides grooved, as indicated at 5, to key with the refractory lining 3, in accordance with known practice in furnace construction.

Other forms of refractory anchor bodies could be used, for example tiles of wedge shape or with serrated sides to key with the lining 3. For employment in an anchorage assembly in accordance with the present invention, a refractory anchor tile or other anchor body need be provided only with a transverse hole near its inner end, such a hole being shown at 6 in the tile 4.

The metal link shown in FIGS. 1, 2 and 3, consists of a pair of U-shaped metal rods 7 which, with their limbs opposed, together make up a substantially rectangular loop and are inserted, from opposite sides, respectively into the hole 6 in the anchor tile 4 and a hole 8 through a bracket 9 on the inside of the furnace casing 1. The ends of the two U-shaped rods 7 meet, or almost meet, to form conjointly one limb through the anchor tile 4 and other limb through the bracket 9. The two rods 7, after insertion, may be held together by an intermediate tie spanning between their bends, such as the wire tie 10 shown in FIG. 3. Such a tie is not essential because the material of the layer 2, shaped to define a closely surrounding recess, prevents escape of the rods 7 after installation.

An alternative form of link is shown by FIG. 4 and comprises one long U-shaped metal rod 11 the limbs of which are inserted completely through the holes of the anchor tile 4 and bracket 9. The link is completed by the ends of the limbs, after insertion, being interconnected by a metal keeper plate or bar 12 with holes through which split ends of the rod 11 are passed and spread as shown at 13.

A further alternative form of metal link is shown by FIG. 5 and consists of a pair of straight metal rods 14 which are separately inserted through the anchor tile and bracket holes and then joined at their ends by a pair of metal keepers 15, like the keeper 12 of FIG. 4. The ends of the rods 14 are shown split, like split pins or cotters before they are spread.

The bracket 9 on the furnace casing, in FIGS. 1 to 3 and 5, consists of a channel-section plate or bar welded or otherwise secured by the edges of its side flanges or walls to the furnace casing so that it forms a sleeve bracket on the furnace casing.

Alternatively a bracket could be made up by two or more U-bolts or like members secured to the furnace casing, like staples in line, for insertion through them of the respective limb of the link retaining the anchor tile. Such a bracket consisting of two U-shaped members 16 is shown in FIG. 4.

For the construction of a furnace lining using the anchorage assemblies of the invention, brackets are provided on the inside of the furnace casing at suitable spaced locations and exposed to the inside through recesses in the thermal insulation layer 2 on the casing 1.

The anchorage assemblies can be incorporated in a refractory lining during the construction thereof in any way which suits the method of construction employed.

For example, in monolithic construction as shown in

FIG. 1, refractory material is placed in situ in successive stages up to the level of each bracket. As each bracket level is reached, each respective anchor tile 4 is then connected to its bracket by insertion of the limbs of its link through the anchor tile and bracket holes and the anchor tile is then embedded in the refractory lining material 3. The link facilitates embedding of the anchor tile in place because it provides a movable retainer for the anchor tile permitting the anchor tile to be pressed down into refractory lining material which has been placed up to or even somewhat above the level of the bracket.

In brick-built construction of a refractory lining, the brickwork can be carried out leaving a space around each bracket on the furnace casing. Through such space there is access to the respective bracket for assembly of an anchor tile and its loop link to the bracket and the anchor tile can then be embedded in the wall by refractory cement or filling material, with or without further brickwork, to fill in the space in the brick-built wall. Preferably, the lining bricks around each bracket location are of wedge shape or have tapered sides so as to provide an inwardly divergent space for key-embedding of the anchor tile.

I claim:

1. In a furnace having a casing structure, an anchorage assembly for a refractory lining of said structure, said assembly comprising a refractory anchor body having sides shaped to key with the refractory lining and having a transverse hole near one end of said anchor body, a bracket on the inside of said structure and having a hole substantially parallel to said hole in said anchor body and metal link means connecting said anchor body to said bracket, said link means being composed of at least two parts providing a pair of substantially parallel limbs extending respectively through said hole in said anchor

body and said hole in said bracket with freedom of relative movement therein.

2. A furnace according to claim 1, in which said link means consists of a pair of U-shaped metal rods of which the limbs extend, from opposite sides respectively, into said holes in said anchor body and said bracket respectively, said rods together making up a substantially rectangular loop.

3. A furnace according to claim 1, in which said link means consists of one long U-shaped metal rod of which the limbs extend completely through said holes in said anchor body and said bracket respectively and a metal keeper secured across the ends of said limbs.

4. A furnace according to claim 1, in which said link means consists of a pair of straight metal rods which extend respectively completely through said holes in said anchor body and said bracket respectively and a pair of metal keepers secured respectively across the opposite ends of said pair of rods.
